MARBLE PACKAGE

Morris Rosenthal, New York, N. Y.

Application January 20, 1934, Serial No. 707,437

2 Claims. (Cl. 206—46)

My present invention relates generally to packaging, and has reference to a new and improved packaged assembly of toy glass marbles.

The merchandising, in packaged units, of toy glass marbles involves unique problems that are not encountered in the packaging of ordinary merchandise. The marbles, by their very nature, are perfect spheres presenting highly polished outer surfaces. To assemble a mass of 10 such bodies, in more or less jumbled relationship, into a bag or the like is, of course, relatively simple but fails to meet the important requirement that the individual marbles be all constantly visible. In the purchasing of marbles, especially by children, the purchaser is largely attracted by the coloration and general appearance of the marbles, and also by the quantity available in a given package. Accordingly, it is highly desirable, if not essential, to display to 20 the prospective purchaser as much as possible of the contents of the package in question.

The various attempts to meet this requirement are reflected in the general development of the art. Ordinary cardboard boxes or the like and 25 ordinary chamois bags are obviously ineffective, except from the pure standpoint of affording accommodation or enclosure for a selected group of marbles. Accordingly, cardboard boxes were devised and attempted in which portions of the 30 walls were perforated or cut out to disclose the contents; and bags of loosely woven mesh were also employed for a similar purpose. Perhaps the greatest degree of visibility of contents was heretofore afforded by the compartmented type 35 of mesh bag described and claimed in United States Letters Patent No. 1,873,640.

It is a general object of my present invention to provide a marble package which serves not only as an inexpensive and feasible enclosure 40 for a group of marbles, but which exposes the contents of the package to the maximum possible degree. More specifically, it is an object of my invention to provide a package in which an enclosure is composed in its entirety of trans- 45 parent material.

In achieving my present general objective I have had to overcome the basic difficulty of maintaining each one of the group of marbles entering into the package in constantly visible 50 relationship to the others. An enclosure of glass or similar rigid material has proven to be unfeasible because of the expense involved and because of the danger in handling and shipping. Ordinary bags or containers of the "cellophane" 55 variety have proven to be inadequate from the

standpoint of strength and unsuitable in maintaining the marbles in any given original relationship.

I have found, however, that where a group of 60 toy glass marbles of substantially equal sizes are arranged in a predetermined contiguous relationship in a single plane, they may be maintained in such relationship by accommodating them within a snug form-fitting enclosure of 65 flexible sheet material, where the material is caused to embody sufficient rigidity to maintain its predetermined prismatic shape. My invention consists, therefore, briefly, in the assembly of a group of toy marbles with a snug 70 enclosure of transparent flexible sheet material 75 in the shape of a prism, preferably a rectangular parallelepiped, the enclosure being caused to embody the requisite rigidity to maintain all of the marbles within it constantly in the original 75 contiguous relationship.

I achieve the foregoing objects and advantages, and such other objects and advantages as may hereinafter appear or be pointed out, in the manner illustratively exemplified in the accompanying drawing, wherein—

Figure 1 is a perspective view of a marble package constructed in accordance with my present invention;

Figure 2 is a longitudinal cross-section taken substantially along the line 2—2 of Figure 1;

Figure 3 is a cross-section taken substantially along the line 3—3 of Figure 1; and

Figure 4 is a plan view of an illustrative blank from which the enclosure may be constructed.

In the illustrated embodiment, a flat blank 90 of transparent flexible sheet material is cut and shaped to the general contour of Figure 4, thereby providing a front wall section 10, a rear wall section 11, a bottom wall section 12, a top wall section 13, and connection flaps 14, 15, and 16. 95 On each of the lateral edges of the sections 10 and 11 I provide side wall extensions 17.

In designing the enclosure, it is important that the width of the bottom wall section 12 and of the top wall section 13 be made substantially 100 equal to the diameter of the marbles to be packaged; whereas the length of each of these sections is made, with as much accuracy as possible, to a predetermined multiple of the diameter, depending upon the arrangement of the marbles 105 to be accommodated. In the illustrated form, I have shown the possible arrangement of a plurality of marbles in three contiguous parallel rows, and the length of the sections 12 and 13 of Figure 4 are, therefore, made substantially 110

equal to three times the diameter of the marbles.

The length of each of the sections 10 and 11 is similarly caused to be of predetermined extent, depending upon the number of marbles to be arranged in each row, the objective being to provide in the finished enclosure a length from top to bottom which is almost exactly the overall length of the group of marbles.

In forming the package, the blank of Figure 4 is folded along the dotted lines, and the adjacent sections 17 are caused to adhere to each other, either by means of adhesive or otherwise, so that an enclosure is ultimately formed having a shape conforming to a rectangular parallelepiped.

15 The connection flaps 14 facilitate the assembly and building up of the enclosure, but the connection flaps 15 and 16 are not connected to the rest of the package until after the contents has been inserted. In other words, the upper end of 20 the package, as viewed in Figure 1, is left open for filling purposes, but it is ultimately sealed by pasting or similarly associating the connection flaps 15 and 16 with the walls of the container, as indicated in Figure 1.

25 As an illustration of one convenient way of arranging the marbles, I have shown three longitudinal adjacent rows 18, and the enclosure, as hereinbefore described, is designed to snugly accommodate and envelop these marbles, the marbles themselves being designated generally by the reference numeral 19.

30 When the package is completed, it will be observed that each of the marbles in the group is constantly visible to the maximum degree. In other words, all surfaces that are not in contact 35 with adjacent marbles of the group are clearly exposed to view. Where the marbles are of a vari-colored character, as they usually are, the sheen and coloration are thus presented to view 40 in a highly attractive manner.

45 The material of the enclosure is purposely made of just sufficient rigidity to cause the enclosure to maintain its original prismatic shape. The material may be of any desired or convenient composition, preferably a cellulosic material. If the material is made to embody too great a thickness, its transparency is affected and the general flexibility and attractive nature of the package is impaired; and if the material 50 is too thin, the insufficient rigidity fails to maintain the marbles in the predetermined contiguous relationship. Those skilled in the art can readily determine from the description given 55 how to determine the degree of rigidity which should be imparted to the material of the enclosure, it being understood that the exact composition does not form an essential part of my invention and that it may vary, depending upon the quantity, sizes, and weights of the marbles 60 entering into the package.

65 While I have illustrated, by way of example, a substantially rectangular package, it will be understood that the marbles may be arranged in other contiguous relationships, e. g., in a triangle; and it will be understood that the marbles are in each case arranged in a single plane so that the thickness from front to back of the package is always substantially equal to the diameter of one marble. The package is 70 thus, in each case, prismatic, but is not necessarily in the form of a rectangular parallelepiped,

although the latter configuration has proven highly satisfactory.

80 The package lends itself readily to association with other packages, in flatwise relationship, for purposes of packaging, stacking, shipping, and display. If desired, each package or a predetermined group of packages may be enclosed in an outer shipping container of cardboard or the like. Each package, however, is complete in itself without any additional outer enclosure and is, in fact, designed to be marketed in the condition herein illustrated.

85 The package is of highly attractive character, the transparent nature of the enclosure lending an additional sheen and attractiveness to it; and the marbles themselves, which are the articles being purchased, are efficiently maintained in constantly visible and contiguous relationship. While the material of the enclosure is flexible, the predetermined rigidity of the material always causes the marbles to return to the original relationship, even after the package has been squeezed or roughly handled, this being due in part to the inherent resilience of 90 the material of the enclosure and to an inherent 95 tendency to return to the shape originally imparted to it.

100 It will be understood that I do not claim, broadly, any transparent packaging of commodities in general, nor do I contend that an 105 enclosure of flexible transparent material is new or is my invention. I do believe, however, that a marble package of the present character is of new and useful character, for the reasons hereinbefore stated.

110 In general, it will be obvious that changes in the details, herein described and illustrated for the purpose of explaining the nature of my invention, may be made by those skilled in the art without departing from the spirit and scope 115 of the invention as expressed in the appended claims. It is, therefore, intended that these details be interpreted as illustrative, and not in a limiting sense.

120 Having thus described my invention, and illustrated its use, what I claim as new and desire to secure by Letters Patent is—

1. A marble package consisting of a plurality of at least four toy glass marbles of substantially equal sizes and arranged in contiguous relation in rows in a single plane, and a prismatic enclosure snugly enveloping the marbles and composed of transparent flexible sheet material having sufficient rigidity to cause the enclosure 125 to retain its shape and maintain the marbles in 130 their original relationship, whereby all of the marbles are constantly visible to the maximum degree.

2. A marble package consisting of a plurality of at least four toy glass marbles of substantially equal sizes and arranged in contiguous rows in a single plane, and an enclosure snugly enveloping the marbles, said enclosure comprising a rectangular parallelepiped of transparent flexible sheet material having sufficient rigidity 135 to cause the enclosure to retain its shape and maintain the marbles in their original relationship, whereby all of the marbles are constantly visible to the maximum degree.

145 MORRIS ROSENTHAL.
